UNITED STATES PATENT OFFICE.

ARTHUR DOCKING, OF NOTTINGHAM, ENGLAND.

GAS AND AIR MIXER.

1,053,793.

Specification of Letters Patent. Patented Feb. 18, 1913.

Application filed July 28, 1911. Serial No. 641,085.

To all whom it may concern:

Be it known that I, ARTHUR DOCKING, a subject of the King of Great Britain, and a resident of Nottingham, in England, have 5 invented a certain new and useful Gas and Air Mixer, of which the following is a specification.

This invention relates to apparatus for supplying a mixture of say for example gas 10 and atmospheric air, for lighting or heating purposes, and refers more particularly to apparatus of the kind in which the two gases are drawn in and compressed to the pressure required by the service, by means 15 of a rotary or other suitable compressor.

The present invention refers to improved means for controlling the supply of gas and air to meet the varying demands of the service, and at the same time maintain the 20 portions of the gas and air constant, under all the different demands of said service.

Apparatus is already well known in which a varying supply of mixture of gas and air in the correct proportions, has been 25 regulated by the pressure on the service side of the compressor, the exhaust side, and in some cases both have been utilized, but owing to the fact that the effective pressure in this class of apparatus is very low, and 30 that the valves have hitherto worked one independently of the other, trouble has been caused by one or more of the controlling valves sticking and either cutting off the supply altogether, or failing to give the 35 proper proportions of gas and air under all conditions.

In the present arrangement the by-pass and inlet controlling valves are positively connected by mechanical means one to the 40 other, and automatically and simultaneously adjusted by the service pressure. Being all mechanically connected together as described, they must move together, and such movements must always be proportionate 45 one to the other, as is predetermined by their mechanical connections, irrespective of any influence which may be separately exerted upon the valves by the velocity of the gases, or by the suction at the inlets.

50 Referring to the drawing, the figure is a

vertical section showing apparatus constructed according to my invention.

An ordinary compressor A of the rotary or other suitable type is employed, and the inlet A¹ of this compressor A, is connected 55 by a pipe B to a gas inlet valve casing C, and by a pipe D to an air inlet valve casing E. The inlet valve casings C and E described, are fitted with valves C¹ and E¹ respectively, and said valves are automatically adjusted so as to admit the proper 60 portions of gas and air required to meet the varying conditions, by means hereinafter described.

The mixed gases, the proportions of 65 which are as already stated controlled by the inlet valves C¹ and E¹ described, are compressed to the required pressure into a service chamber G, which is connected to the outlet A² of the compressor A, by means 70 of a pipe H, and from this chamber G the gases are conveyed to the required points, by one or more service pipes J connected to said chamber G.

The inlet valve casings C and E previously referred to, are divided between their respective inlets and outlets by horizontal partitions C² and E² respectively, and the valves C¹ and E¹ which are preferably of the cylindrical type, work in circular openings of the same size in the respective partitions. The valves C¹ and E¹ which are closed at the top and open at the bottom, are provided with ports C³ and E³ in 80 their cylindrical walls, so that the effective 85 area of the actual inlet openings, can be varied by raising and lowering the said valves to a more or less extent. This is effected through the intermediary of their respective valve stems C⁴ and E⁴, which are 90 carried through stuffing boxes at the top of the respective casings C and E in the usual manner.

Situated above the service chamber G is a by-pass casing F, fitted with a by-pass valve 95 K of the piston type. The lower end of the casing F is open to the service chamber G, while a port F¹ in its side, which is normally closed by the by-pass valve K, is connected by a pipe L to the pipe B in connec- 100

tion with the inlet A¹ of the compressor A. The stem K¹ of the by-pass valve is carried up and is attached to a flexible diaphragm M, situated in a diaphragm chamber N carried above the by-pass casing F.

The space in the diaphragm chamber N on the underside of the diaphragm M, is connected to the service chamber G, preferably by means of a pipe O having a restricted opening, so that the action of the said diaphragm M which is controlled by the pressure in the said chamber G, shall be steady under sudden changes of pressure.

The stem K¹ of the by-pass valve K is carried up above the diaphragm M and out through an opening in the top diaphragm chamber N, and its upper end is connected by levers P P¹ and links P² P³, to the stems C¹ and E¹ of the respective inlet valves C¹ and E¹, which are for convenience situated on opposite sides of the said diaphragm chamber N.

The arrangement described is so disposed, that the inlet valves C¹ and E¹ are lowered and thus closed to a more or less extent, when the by-pass valve K is raised. The amount of closing movement imparted to the respective inlet valves C¹ and E¹ relatively to the opening movement of the by-pass valve K, is in each case determined by the disposition of the fulcrums on the respective levers P and P¹, which are carried by the upper free ends of arms Q Q¹ respectively, pivoted to the top of the diaphragm casing N.

The operation of the apparatus is as follows:—The diaphragm M in connection with the by-pass valve K is weighted according to the pressure required in the service, and when this pressure is exceeded, owing to the demand being less than the supply from the compressor A, the said diaphragm M and the by-pass valve K are raised, thus opening the port F¹ and permitting the surplus mixture to pass by way of said port and pipe L back to the compressor A again. At the same time the by-pass valve K is opened, the inlet valves C¹ and E¹ are closed to an extent determined by their respective connections, so that they will only admit sufficient gas and air to maintain the pressure in the service chamber G, while the mixed gases in the apparatus above and beyond the demands of the service for the time being, are constantly circulated by the compressor A as is usual, passing from the service chamber G into the by-pass casing F, and then from the latter by way of the port F¹ and pipe L back to the compressor again.

The gas may be supplied to the gas inlet valve casing C at atmospheric pressure, by employing a regulator or governor of the usual construction.

In the arrangement described, the inlet valves C¹ and E¹ being positively connected

to and closed when the by-pass valve K is opened, and the latter being controlled by the full pressure of the gas in the service chamber G, it not only follows that all of the valves described always work in unison, and there is consequently no risk of either of them sticking, but when the apparatus is out of action, the by-pass valve is quite closed, and the inlet valves C¹ and E¹ necessarily wide open, so that in starting the full supply is first obtained, before the said valves are closed or partially closed, in order to cut down the supply to meet the existing demand.

What I claim as my invention and desire to cover by Letters Patent is:—

1. In apparatus for supplying a mixture of gas and air or the like, the combination of a compressor, a by-pass, a by-pass valve for regulating the return of the surplus mixture to the suction side of the compressor, means for controlling said valve, inlet valves for controlling the supply of air and gas admitted to the compressor, and means for connecting the said inlet valves to the by-pass valve whereby the former are positively closed proportionately to the opening of the latter, substantially as described.

2. In apparatus for supplying a mixture of gas and air or the like, the combination of a compressor, a by-pass, a by-pass valve for regulating the return of the surplus mixture to the suction side of the compressor, a diaphragm subject to the service pressure for controlling said valve, inlet valves for controlling the supply of air and gas admitted to the compressor, and means for connecting said inlet valves to the by-pass valve whereby the former are positively closed proportionately to the opening of the latter, substantially as described.

3. In apparatus for supplying a mixture of gas and air or the like, the combination of a compressor, a by-pass, a by-pass valve for regulating the return of the surplus mixture from the service to the suction side of the compressor, a diaphragm which is subject to the service pressure for controlling the said valve, inlet valves for controlling the supply of air and gas admitted to the compressor, and a system of levers connecting the said inlet valves to the by-pass valve and positively closing the former proportionately to the opening of the latter, substantially as described.

4. In apparatus for supplying a mixture of gas and air or the like, the combination of a compressor, a by-pass, a service chamber which is connected to both the service and suction side of the compressor, a by-pass valve for regulating the return of the surplus mixture from said service chamber to the compressor, a diaphragm chamber connected to the service chamber, a diaphragm

in said chamber connected to and controlling the by-pass valve, inlet valves for controlling the supply of air and gas admitted to the compressor, and a system of levers for connecting said inlet valves with the by-pass valve and positively closing the former proportionately to the opening of the latter, substantially as described.

In testimony whereof I have signed my name to this specification in the presence of 10 two subscribing witnesses.

ARTHUR DOCKING.
